Primary Examiner — Omeed Agilee(57) **CLAIM**

The ornamental design for a test strip detection device, as shown and described.

DESCRIPTION

FIG. 1 is a perspective view of a test strip detection device showing our new design;

FIG. 2 is a front view thereof, the back view, left view, and the right view are identical to FIG. 2;

FIG. 3 is an enlarged top view thereof;

FIG. 4 is an enlarged bottom view thereof; and,

FIG. 5 is an enlarged perspective view of area 5 encircled in FIG. 1.

The broken lines shown on the drawings depict portions of the test strip detection device that form no part of the claimed design.

1 Claim, 5 Drawing Sheets(56)
